Inventor:

Leopold Stürzwage,
By J. M. Dower, Attorney,

UNITED STATES PATENT OFFICE.

LEOPOLD STÜRZWAGE, OF MOSCOW, RUSSIA.

PIANO MECHANISM.

SPECIFICATION forming part of Letters Patent No. 592,840, dated November 2, 1897.

Application filed June 22, 1897. Serial No. 641,804. (No model.)

To all whom it may concern:

Be it known that I, LEOPOLD STÜRZWAGE, a subject of the Emperor of Russia, residing at Moscow, Russia, have invented certain 5 new and useful Improvements in Piano Mechanics, of which the following is a specification.

The present invention relates to repeating mechanism for grand pianos and involves the 10 peculiar construction of the jack and fly-jack, by means of which an even, light, and noiseless stroke or blow, as also reliability of repetition, is obtained.

In order to render the present specification 15 more easily intelligible, reference is had to the accompanying drawings, in which similar letters of reference denote similar parts throughout the several views.

Figure 1 is a side elevation of the device, 20 showing the hammer down. Fig. 2 is a similar elevation drawn to a larger scale with the hammer raised, and Fig. 3 a front elevation of Fig. 2.

The jack *a* is pivoted at *a'* and provided at 25 one end with a cushion *a'*, on which the stem *b* of the hammer rests, said jack carrying the fly-jack *c* at the opposite end, having its pivot arranged approximately over the rigidly-fixed striker-pin *d*. The end of the fly-jack is bi- 30 furcated and embraces the jack *a*, enabling a small spring *e*, mounted on the jack *a*, to pass between the bifurcations and engage a cord-eye fastened on the lower surface of the projecting foot *c'* of the fly-jack. The up- 35 wardly-extending surface of the foot *c'* is provided with a cushion and is adapted when the key is struck to engage the fixed stop *f*, which is adjustable by means of a screw *f'* and operates to throw the fly-jack out of engage- 40 ment with the knob *b* of the hammer-stem. The upper part of the fly-jack is narrowed to 45 enable it to pass through an orifice *g'* of the repeater-lever *g*, in which orifice it has sufficient play to prevent friction. Above the orifice the fly-jack is again widened, so that 50 its upper edge is of the same width as the knob or projection *b'* on the stem of the hammer and also as the raised shoulder *g''* of the repeater-lever *g*.

When the key is struck, the hammer *b* is 55 first raised by the fly-jack *c* until it has nearly attained a horizontal position, when the knob *b'* passes onto the shoulder *g''*, Fig. 2, the fly-jack being thrown out of engagement by the stop *f* without causing the slightest fric-

tion on the knob *b'*. In effecting the repetition the fly-jack will, with equal ease, again slip under the knob or projection *b'*. The disengagement of the lever *g* will be effected by the stop *h* without causing any friction. A 60 screw *i* in the lever *g* forms a stop to prevent the fly-jack *c* from being thrown too far back from the knob *b'*. The said screw *i* also forms a stop for the lever *g* itself after it has been thrown out of engagement. The spring *k*, 65 which is bent round at an angle, is adjustable in the jack *a* by means of a screw *k'*. Said spring engages a cord-eye fastened to the lever *g*. The adjusting-screw enables an exact adjustment of the spring *k* for the heavier 70 bass and lighter soprano hammers.

The raised shoulder *g''* of the repeater-lever enables the fly-jack to be made broader at its upper end, which has the effect of preventing the same from getting pressed into the 75 knob *b'*, as has hitherto been the case, thus causing considerable friction on the disengagement of the fly-jack. Both the jack and the repeater-lever will thus be disengaged without causing any friction whatever, so that 80 no noise whatever can be caused by the present mechanism, since the springs will work entirely noiselessly in their cord-eyes.

I claim as my invention—

1. In a repeating mechanism for grand pianos the combination of the jack *a* with the repeater-lever *g* mounted on the jack and having a raised shoulder *g''* and an orifice *g'* before said shoulder, and a fly-jack *c* mounted on the jack *a*, the said fly-jack passing 90 through the orifice *g'* of the lever *g* and having its upper edge widened to the width of the knob *b'* of the hammer-stem, substantially as described.

2. In a repeating mechanism for grand pianos the combination of the jack *a* the repeater-lever *g* with slot *g'* end shoulder *g''* and the fly-jack *c* having a widened upper edge, with the stop *f* disengaging the fly-jack in its upward movement and the stop *i* screwed in 95 the repeater-lever *g*, the stop *i* limiting the backward movement of the fly-jack, substantially as described.

In testimony whereof I have signed my name to this specification in the presence of 105 two subscribing witnesses.

LEOPOLD STÜRZWAGE.
